APPARATUS AND METHOD OF ELIMINATING
SIGNAL FADING

Lewis D. Eckard, Washington, D. C.

Application October 6, 1938, Serial No. 223,688

22 Claims. (Cl. 259—30)

The present invention relates to means for the automatic change in the capacity of the condenser or condensers in wave receiving means with variations of atmospheric pressure.

Fading is a phenomenon which has always been troublesome in signal receiving sets.

The earth's surface is belted with a continuously moving band of air. The current of air generally flows from west to east. The band of continuously moving air varies in height throughout its path and at any given point on the earth's surface the atmospheric pressure varies due to the increasing and decreasing height of the column of air thereover. It is the continuous movement of this layer of air with its variance in height that causes variations in barometric pressure. The higher the column of air over any given point on the earth's surface the greater the barometric pressure and correspondingly, the lower the column of air, the lower the barometric pressure. This movement of the air current over the earth's surface causing variations in barometric pressure at a given point is known as the primary variations in atmospheric pressure.

Beyond the moving layer of air which overlies the earth and which gives rise to the primary variations in atmospheric pressure, is a secondary layer. In this secondary layer there are minute variations of the air pressure which occur all the time in more or less uniformity. These variations are called the secondary variations of atmospheric pressure and possess a pulsating movement.

It was found by experiment that radio signals, particularly those signals received as sky waves, faded most when the barometric readings varied extensively and that it was necessary to adjust the capacity of the tuning condensers of the radio receiver before the signal could be brought back to its original volume. As the barometric pressure increased the frequency of the signal increased and it was necessary to decrease the capacity of the tuning condensers to again obtain resonance. Also, as the atmospheric pressure decreased it was necessary to increase the capacity of the tuning condensers in the radio circuit to regain resonance. This proves that the frequency of a wave or signal varies according to the change in atmospheric pressure and it is immaterial whether the sending station is crystal controlled or not.

Experiments show the following:

Barometric change in inches of mercury frequency change in kilo-cycles:

	Kilo-cycles
0.001"	(approximately) 0.05
0.01"	do 0.5
0.1"	do 5.0

From the above table it can readily be seen that variations in atmospheric pressure cause a frequency drift.

Now it is believed that this frequency drift is for the most part caused by the secondary variations, which possess a pulsating wave movement. This pulsating movement causes a change in the magnet flux density of the ionized layer which contains ozone, a magnetic gas. During a contracting or crowding period of the molecules and ions in the secondary layer, the magnetic field is shortened resulting in an increased number per unit area of electrostatic and magnetic fields thereby increasing the frequency of the radio wave travelling therethrough. During periods of depression or rarefaction the magnetic fields are lengthened and the electrostatic fields are further apart resulting in a lower frequency of the wave passing therethrough.

This pulsating or secondary wave movement could be caused by the concerted pulsation of the molecules of the atmosphere due to the absorption of energy from the cosmic rays. It is known that molecules are composed of positive protons in a nucleus and have negative electrons revolving about the protons in various energy levels. The electrons of any one molecule absorb energy from the cosmic rays and the protons of that molecule radiate the absorbed energy. It creates a pulsation in the molecules similar to the movement of the lungs in breathing. Our lungs expand when we absorb or take in air and contract when we radiate or exhale the used air.

It is to be understood that the theory is advanced only as an aid in understanding the invention and that a paper is to be published at a later date giving a detailed explanation of secondary variations in atmospheric pressure.

It is broadly the concept of this invention to provide a variable reactance device responsive to minute variations in atmospheric pressure and which automatically cooperates with the tuning circuit of a wave receiving set to substantially eliminate signal fading due to the minute variations in atmospheric pressure, and wherein the receiving set is kept in complete resonance. Complete resonance depends upon a proper relation between the capacity, inductance and resistance in the tuning circuit. A frequent shift

in the carrier wave, unless compensated for, would destroy complete resonance in the tuning circuit and give the effect of fading in the wave receiving set. To compensate for the frequency shift of the carrier wave due to minute variations in atmospheric pressure, the variable reactance device which is responsive to the minute atmospheric variations, is placed in the tuning circuit of the wave receiving set, so that any minute variation in atmospheric pressure causes a variation in the reactance device to maintain the tuning circuit resonant to the frequency of the carrier wave.

The present invention has for its primary object the provision of a variable condenser which is sensitive to primary and secondary variations in atmospheric pressure and which cooperates with a wave receiving device to automatically eliminate fading.

The present invention is adapted to be used in combination with any wave receiving means, such as radio telephone, telegraph, television, selective ringing, radio telephone circuits, directional finders, beams, depth indicators or in any other system or circuit which depends on radio waves being propagated through the atmosphere or water and which is tuned to resonance by varying capacity, inductance or resistance.

An object of the invention is to eliminate signal fading in all wave receiving devices and more particularly in radio receiving sets.

Another object is to provide condenser means having a variable capacity controlled by atmospheric pressure and cooperating with tuning condensers to eliminate signal fading in receiving sets.

Another object is to provide an automatic barometrically controlled variable condenser cooperating with the tuning condensers of signal receiving means to eliminate tonal volume changes.

Another object is to provide variable condenser means, the capacity of which is automatically responsive to barometric pressure changes and which cooperates with tuning condensers in wave receiving means to eliminate fading.

Another object is to provide a small inexpensive auxiliary condenser having a thin metallic disk adapted to pulsate with slight variations in barometric pressure to vary the capacity thereof and which may be inserted in the tuning circuit of a wave receiving device either in parallel or in series with the tuning condensers thereof to automatically alter the capacity of the tuning condensers and to thus eliminate fading.

Another object is to provide means responsive to atmospheric pressure changes and associated with a wave receiving device to substantially compensate for the frequency drift of the carrier wave due to atmospheric pressure changes whereby the frequency of the carrier wave is maintained in resonance with the wave receiving device.

Another object is to eliminate extraneous noises in the wave receiving set such as the sound comparable to the noise of the ocean waves.

Another object is to provide a wave receiving device whereby all stations can be push button controlled.

Another object is to provide a variable condenser in which mercury, which is responsive to minute and major atmospheric pressure changes,

serves as one of the electrodes of the said condenser.

Another object is to provide an auxiliary variable condenser sensitive to secondary and primary variations in atmospheric pressure which electrically cooperates with the tuning condensers of a radio set so that broadcasting stations always come in at their proper location on the dial.

Other and further objects and advantages will be apparent from the following specification and the claims appended thereto.

In the drawings where like numerals refer to like or corresponding parts throughout the several views,

Figure 1 is a diagrammatic view perspectively showing a vacuum cell condenser in the electrical tuning circuit of a radio receiver and embodying the principal features of the invention.

Figure 2 is a plan view of the plates to be used as a condenser in conjunction with its vacuum cell, all shown in Fig. 1.

Figure 3 is a plan view of a vacuum cell variable condenser and showing three conducting plates insulated from each other.

Figure 4 is a front elevation of the vacuum cell condenser showing the corrugated surface thereof.

Figure 5 is a top plan view with parts broken away of a modified vacuum cell variable condenser in the radio circuit.

Figure 6 is a side elevation with parts broken away of the modified vacuum cell condenser showing the corrugated outer and inner surface of the cell.

Figure 7 is a side elevation of the modified vacuum cell condenser, and

Figure 8 is a front elevation of a mercurial barometer condenser to be used as a variable condenser in the radio circuit.

Referring now to the drawings and more particularly to Figure 1, the numeral 28 generally indicates a vacuum cell provided with a corrugated surface having a plurality of integrally connected corrugated sections 24 which are adapted to pulsate freely with minute variations in atmospheric pressure. One of the pulsatable sections is grounded, as at 22, in any conventional manner. Spaced from said grounded plate are a plurality of insulated conducting plates, 23, 24, and 25, each of which is provided with a projecting lug 23a, 24a, and 25a, respectively. The said plates are preferably made of metal but may be composed of any conducting substance. The said plates are further insulated from each other and from the said grounded corrugated sections which are sensitive to minute atmospheric pressure variations. The vacuum cell as described above, per se, is well known in the barometer art, and any type of vacuum cell known today which is sensitive to minute variations in atmospheric pressure would be suitable for accomplishing the purposes of this invention. The vacuum cell condenser, as described, is a multi-plate automatically variable condenser, the capacity of which is automatically changed with the pulsations of the grounded corrugated plate which is sensitive to minute variations in atmospheric pressure. Of course, for some uses it may be advisable to have a variable condenser having only one relatively fixed conducting plate, or a plurality of said condensers in series, parallel or series-parallel relation, or a plurality of multi-plate condensers in series, parallel, or series-parallel relation, and this invention is in

tended to cover such combinations. The size and number of the conducting plates and vacuum cell may be changed to meet different capacity requirements.

8 Still referring to Figure 1, 23b indicates a radio frequency tube, 23c an inductance coil, 23d a variable tuning condenser and 23e a smaller variable condenser known as a trimmer, all of which are in an electrical tuning circuit with the plate 23.

10 Likewise, the detector tube 24b, the inductance coil 24c, the variable tuning condenser 24d and the trimmer 24e are in the electrical tuning circuit with the plate 24.

12 And the oscillating tube 25b, the inductance coil 25c, the variable tuning condenser 25d and the trimmer 25e are in the electrical tuning circuit with plate 25.

14 Figure 1, as described, is a standard super-heterodyne radio tuning circuit having one radio frequency amplifier tube 23b, one first detector or mixer tube 24b, and the local oscillator tube 25b. The tubes 23b, 24b, and 25b are each in circuit with the plates 23, 24 and 25 of the auxiliary condenser respectively. The pressure sensitive grounded vacuum cell 26 when it pulsates with minute atmospheric variations causes an automatic and simultaneous capacity change in the radio frequency, detector and oscillator tuning circuits.

16 Referring now to Figures 3 and 4 the vacuum cell 26 is shown suspended in a housing comprising a base plate 28, upright members 27 and 29. A disk 29 which carries the conducting plates 23, 24 and 25 is secured to the vertical members 27 and 29 at the upper ends thereof by means of screws 28a. The conducting plates 23, 24 and 25 which are disposed on the underside of the disk 29 are insulated from each other and from the conducting vacuum cell 26. The movement of the vacuum cell 26 closer to or further from the plates 23, 24 and 25 increases or decreases the capacity of the condenser by changing the width of the dielectric. The vacuum cell 26 is secured at the lower end thereof to the screw member 28 which threadedly engages through the plate 29. The screw member 28 is adapted to be turned and the vacuum cell 26 can be moved into a closer position with respect to the conducting plates 23, 24 and 25, i. e. the air gap between the cell and the plates can be selectively increased or decreased to decrease or increase the capacity of the condenser. Once it is properly set it seldom requires adjustment.

18 Referring now to Figures 5, 6 and 7 of the drawings, a further modification of the type of vacuum cell which can be used as an automatically variable condenser is shown. The numeral 41 indicates generally a vacuum cell condenser, the vacuum cell being the type used in an aneroid barometer vacuum cell type. This type of barometer is generally known in the barometer art and in Charles J. Tagilabue Mfg. Co.'s Illustrated Catalogue at page 263 a full description is given of the structure thereof. For the purpose of this invention 42 indicates a vacuum cell composed of two disks of corrugated German silver or the like which have been soldered together and from which the air has been exhausted. A spring 42a keeps the vacuum cell 42 from collapsing. The vacuum cell has the lower surface thereof secured to the plate 43. The plate 44 is spaced from plate 43 in any suitable manner and carries on its underside a plurality of conducting plates preferably corrugated, insulated from one another. The plates 43 and 44 are preferably composed of insulating material. The conducting plates of the vacuum cell condenser, generally indicated at 41, one of which is indicated at 45 in Figure 5, each has a lug such as 45a projecting therefrom which is adapted to connect each of the conducting plates of the vacuum cell condenser into the tuning circuit of a signal receiving device in a manner similar to that shown in Figure 1.

10 In operation, the conducting plates of the condenser are connected into the tuning circuit of a wave receiving set in a manner similar to that shown in Figure 1. The vacuum cell is suitably grounded. The complete device is now an automatically variable condenser sensitive to minute variations in atmosphere pressure. Minute variations in atmospheric pressure cause the corrugated upper surface of the cell 42 to move and either increase or decrease the width of the air gap between the said surface of the vacuum cell and the corrugated under surface of the conducting plates, thus either decreasing or increasing the capacity of the condenser automatically. The air gap as shown in Figure 6 is exaggerated but must be of sufficient width to allow for major and minor atmospheric pressure changes, and the movement of the surface of the vacuum cell is generally only in the neighborhood of 0.001 to 0.1 inch of mercury, that is, the variations in barometric pressure due to the secondary variations of the atmosphere. The more sensitive the cell used the more exactly the capacity change follows the minute variations in atmospheric pressure.

15 Referring now to Figure 8, there is shown a glass tube 50 containing mercury 50a, and having a closed end 51, an open end 52 and an elbow portion 53. The mercury 50a in the tube 50 is balanced by atmospheric pressure and as it is undamped it is very sensitive to slight or minute variations in the said pressure. A plurality of conducting plates 54, 55 and 56 are copper plated to the tube 50 at a point adjacent the open end 52 thereof. The conducting plates have lugs 54a, 55a and 56a respectively projecting therefrom which are adapted to be connected into the electrical tuning circuit of a wave receiving set in a manner as shown in Figure 1. The plates 54, 55 and 56 are insulated from each other. The mercury 50a is disposed in tube 50 of glass or the like, so that the surface thereof near the opening 52, is substantially midway the height of the conducting plates 54, 55 and 56, to allow for the severe primary movements of the atmosphere. It is to be understood that the mercury surface near the opening 52 must lie in the same horizontal plane as the conducting plates 54, 55 and 56, otherwise minute atmospheric pressure changes would produce no capacity change in the tuning circuits of the wave receiving device. The mercury 50a can be grounded directly by placing a wire directly in contact with the mercury through the opening 52, or a capacity ground can be used by securing a metal band 58b to the tube 50 at a point preferably above the elbow 53 on the longer arm of the tube 50 and grounding the metal band as at 58c. It is preferred to directly ground the mercury.

20 The mercury barometer condenser as described is an automatically variable condenser sensitive to minute variations in atmospheric pressure. The capacity of the variable condenser is automatically changed with minute variations in barometer pressure and when the condenser is 25

electrically connected in the tuning circuit of a signal receiving set, as shown in Figure 1, the capacity of the tuning condensers is automatically changed and the set remains in resonance and signal fading is prevented. Radio broadcasting stations equipped with radio receiving sets provided with this auxiliary pressure sensitive mercury barometer condenser will be able to pick up distant signals with substantially no fading and re-broadcast the same.

The vacuum cells used could be of any dimensions or made of any material which could withstand considerable pressure. A vacuum cell having a diameter of two inches and a height of 15 3 1/4 inches was found to be a convenient size.

Further modifications will be apparent to those skilled in the art and it is desired, therefore, that the invention be limited only by the prior art and the scope of the appended claims.

20 Having thus described my invention, what I claim as new and desire to secure by Letters Patent is:

1. That method of substantially compensating for the frequency drift of the carrier wave due 25 to atmospheric pressure changes and received by a wave receiving device, which comprises maintaining the receiving device in resonance with the frequency of the carrier wave in response to atmospheric pressure changes at the 30 wave receiving device.

2. A radio receiver having at least one tunable high frequency circuit comprising reactance of opposite sign, one of which is adjustable, for the selective reception of carrier frequencies 35 throughout a range of frequencies, which frequencies are subject to a shift in frequency in transmission through space due primarily to minor barometric pressure variations, means responsive to the said pressure variations to produce synchronized reactance variations of one sign, and means operatively coupling said last-named means in said tunable circuit in such manner that the tunable circuit, after being tuned to resonance by said adjustable reactance 45 to a selected one of said carrier frequencies, is maintained in resonance to that carrier frequency as received due to the synchronized reactance variations therein.

3. In combination with the tuning circuit of 50 a wave receiving set arranged to receive waves transmitted through space from a remote point and subject to frequency drift due to changes in atmospheric pressure, said circuit being provided with a main tuning condenser and an auxiliary 55 automatically variable condenser comprising a conducting portion, and a movable conducting portion insulated from and cooperating with said first mentioned conducting portion and responsive to minute changes in atmospheric pressure for maintaining said tuning circuit in resonance with the frequency of said waves, whereby apparent fading of said waves due to frequency drift is substantially eliminated in said receiving set.

65 4. In combination with the tuning circuit of a wave receiving set arranged to receive waves transmitted through space from a remote point and subject to frequency drift due to changes in atmospheric pressure, said circuit being provided 70 with a main tuning condenser and an auxiliary automatically variable condenser comprising a relatively fixed conducting portion, and a second relatively movable conducting portion insulated from and cooperating with said first mentioned portion and responsive to minute

changes in atmospheric pressure for maintaining said tuning circuit in resonance with the frequency of said waves, whereby apparent fading of said waves due to frequency drift is substantially eliminated in said receiving set.

5. In combination with the tuning circuit of a wave receiving set arranged to receive waves transmitted through space from a remote point and subject to frequency drift due to changes in atmospheric pressure, said circuit being provided with a main tuning condenser and an auxiliary automatically variable condenser comprising a conducting portion, and a conductive vacuum cell insulated from and cooperating with said first mentioned conducting portion and responsive to minute changes in atmospheric pressure for maintaining said tuning circuit in resonance with the frequency of said waves, whereby apparent fading of said waves due to frequency drift is substantially eliminated in said receiving set.

6. In combination with the tuning circuit of a wave receiving set arranged to receive waves transmitted through space from a remote point and subject to frequency drift due to changes in atmospheric pressure, said circuit being provided with a main tuning condenser and an auxiliary automatically variable condenser comprising a conducting portion, and a conductive vacuum cell insulated from and cooperating with said first mentioned conducting portion and responsive to minute changes in atmospheric pressure for maintaining said tuning circuit in resonance with the frequency of said waves, whereby apparent fading of said waves due to frequency drift is substantially eliminated in said receiving set, and spring means cooperating with said vacuum cell to prevent collapse thereof.

7. In combination with a wave receiving system of the superheterodyne type arranged to receive waves transmitted through space from a remote point and subject to frequency drift due to atmospheric pressure changes, said system comprising a tunable radio frequency circuit, a tunable first detector circuit and a tunable oscillator circuit, each circuit having a main tuning condenser; an auxiliary automatically variable condenser comprising three conducting plates insulated from each other and each connected respectively to one of said circuits, and a movable conducting portion insulated from said three plates and cooperating therewith and connected to said tunable circuits and responsive to minute changes in atmospheric pressure for maintaining said radio frequency and first detector circuits in resonance with the frequency of said received waves and proportionately changing the frequency of the oscillator circuit, whereby apparent fading of said waves due to frequency drift is substantially eliminated in said receiving system.

8. In combination with a wave receiving system arranged to receive waves transmitted through space from a remote point and subject to frequency drift due to atmospheric pressure changes, said system comprising a plurality of tuning circuits each having a main tuning condenser an auxiliary automatically variable condenser comprising a plurality of conducting plates insulated from each other and each being respectively connected to one of said tuning circuits, and a movable conducting portion insulated from said plurality of plates and cooperating therewith and connected to said tuning circuits and responsive to minute changes in at-

mospheric pressure for simultaneously maintaining said tuning circuits in resonance with the frequency of said received waves, whereby apparent fading of said waves due to frequency drift is substantially eliminated in said receiving system.

9. In combination with a wave receiving system arranged to receive waves transmitted through space from a remote point and subject to frequency drift due to atmospheric pressure changes, said system comprising a plurality of tuning circuits each having a main tuning condenser; an auxiliary automatically variable condenser comprising a non-conducting J-shaped tube provided with an open end and having mercury therein forming a movable vertical column sensitive to minute changes in atmospheric pressure, and a plurality of conducting plates insulated from each other and from the mercury column, and carried by said tube, each of said plates being respectively connected to each of said tuning circuits and cooperating with said mercury column which is connected to said tuning circuits and to maintain said tuning circuits in resonance with the frequency of said received waves in response to movement of said mercury column due to changes in atmospheric pressure, whereby apparent fading of said waves due to frequency drift is substantially eliminated in said receiving system.

10. In combination with the tuning circuit of a wave receiving set arranged to receive waves transmitted through space from a remote point and subject to frequency drift due to changes in atmospheric pressure, said circuit being provided with a main tuning condenser and an auxiliary automatically variable condenser comprising a conducting portion, a movable conducting portion insulated from and cooperating with said first mentioned conducting portion and responsive to minute changes in atmospheric pressure for maintaining said tuning circuit in resonance with the frequency of said waves, whereby apparent fading of said waves due to frequency drift is substantially eliminated in said receiving set, and manually operated adjusting means for initially selecting the capacity of said auxiliary condenser.

11. In the operation of a receiving device having a tuning circuit for receiving waves transmitted through space from a remote point, that method of substantially eliminating the apparent fading of said waves due to frequency shift caused by atmospheric pressure changes, which comprises automatically varying the reactance of the tuning circuit in response to minute variations in atmospheric pressure to maintain said tuning circuit resonant to the frequency of the received waves.

12. In the operation of a receiving device having a tuning circuit for receiving waves transmitted through space from a remote point, that method of substantially eliminating the apparent fading of said waves due to frequency shift caused by atmospheric pressure changes, which comprises automatically varying the capacity of the tuning circuit in response to minute variations in atmospheric pressure to maintain the tuning circuit resonant to the frequency of the received waves.

13. In combination with the tuning circuit of a wave receiving device arranged to receive waves transmitted through space from a remote point and subject to frequency drift due to changes in atmospheric pressure, an automatically variable

reactance device responsive to minute changes in atmospheric pressure for maintaining said tuning circuit in resonance with the frequency of said received waves, whereby apparent fading of said waves due to frequency drift is substantially eliminated in said receiving device.

14. In combination with the tuning circuit of a wave receiving device arranged to receive waves transmitted through space from a remote point and subject to frequency drift due to atmospheric pressure changes, an automatically variable reactance device responsive to variations in atmospheric pressure of less than 0.02 inch of mercury for maintaining said tuning circuit in resonance with the frequency of said received waves, whereby apparent fading of said waves due to frequency drift is substantially eliminated in said receiving device.

15. In combination with the tuning circuit of a wave receiving device arranged to receive waves transmitted through space from a remote point and subject to frequency drift due to atmospheric pressure changes, a main tuning reactance device, an auxiliary automatically variable reactance device responsive to variations in atmospheric pressure of less than 0.02 inch of mercury for maintaining said tuning circuit in resonance with the frequency of said received waves, whereby apparent fading of said waves due to frequency drift is substantially eliminated in said receiving device.

16. In combination with the tuning circuit of a wave receiving device arranged to receive waves transmitted through space from a remote point and subject to frequency drift due to atmospheric pressure changes, an automatically variable condenser responsive to variations in atmospheric pressure of less than 0.02 inch of mercury for maintaining said tuning circuit in resonance with the frequency of said received waves, whereby apparent fading of said waves due to frequency drift is substantially eliminated in said receiving device.

17. In combination with the tuning circuit of a wave receiving device arranged to receive waves transmitted through space from a remote point and subject to frequency drift due to atmospheric pressure changes, a main tuning reactance device, an auxiliary automatically variable condenser responsive to variations in atmospheric pressure of less than 0.02 inch of mercury for maintaining said tuning circuit in resonance with the frequency of said received waves, whereby apparent fading of said waves due to frequency drift is substantially eliminated in said receiving device.

18. In combination with the tuning circuit of a wave receiving device arranged to receive waves transmitted through space from a remote point and subject to frequency drift due to changes in atmospheric pressure, a main tuning condenser for tuning said circuit to the frequency of said received waves, and an auxiliary automatically variable tuning condenser in parallel with said main condenser and responsive to minute variations in atmospheric pressure for maintaining said tuning circuit in resonance with the frequency of said received waves, whereby apparent fading of said waves due to frequency drift is substantially eliminated in said receiving device.

19. In combination with the tuning circuit of a wave receiving device arranged to receive waves transmitted through space from a remote point and subject to frequency drift due to changes in atmospheric pressure, a main tuning reactance

device for tuning said circuit to the frequency of said received waves, and an auxiliary automatically variable tuning reactance device in parallel with said main reactance device and responsive to minute variations in atmospheric pressure for maintaining said tuning circuit in resonance with the frequency of said received waves, whereby apparent fading of said waves due to frequency drift is substantially eliminated in said receiving device.

20. In a wave receiving device, a tuning circuit arranged to receive waves transmitted through space from a remote point and subject to frequency drift due to changes in atmospheric pressure, said circuit including tuning means adapted to be adjusted to tune said circuit to any frequency within the range for which the receiving device is intended, and an auxiliary variable reactance device responsive to minute variations in atmospheric pressure for automatically altering the frequency to which the circuit is initially tuned so that said circuit is maintained in resonance with the frequency of said received waves as their frequency drifts, said automatic alterations being a small fraction of the change that the adjustable tuning means can produce, whereby apparent fading of said received waves due to frequency drift is substantially eliminated in said receiving device.

25. 21. In a wave receiving device, a tuning cir-

cuit arranged to receive waves transmitted through space from a remote point and subject to frequency drift due to changes in atmospheric pressure, said circuit including tuning means adapted to be adjusted to tune said circuit to any frequency within the range for which the receiving device is intended, and an auxiliary variable condenser responsive to minute variations in atmospheric pressure for automatically altering the frequency to which the circuit is initially 10 tuned so that said circuit is maintained in resonance with the frequency of said received waves as their frequency drifts, said automatic alterations being a small fraction of the change that the adjustable tuning means can produce, whereby apparent fading of said received waves due to frequency drift is substantially eliminated in said receiving device.

22. In combination with a tuning circuit of a wave receiving device arranged to receive waves transmitted through space from a remote point and subject to frequency drift due to changes in atmospheric pressure, means responsive to changes in atmospheric pressure for maintaining said circuit in resonance with the frequency of 25 said received waves, whereby apparent fading of said waves is substantially eliminated in said receiving device.

LEWIS D. ECKARD. 30
